UNITED STATES PATENT OFFICE.

BURNHAM C. STICKNEY, OF PORTSMOUTH, NEW HAMPSHIRE, ASSIGNOR TO UNDERWOOD TYPEWRITER COMPANY, OF NEW YORK, N. Y., A CORPORATION OF DELAWARE.

TYPEWRITING MACHINE.

Application filed December 11, 1925. Serial No. 74,667.

This invention relates to machines for typ-
ing upon fan-fold webs, and particularly to
means for slitting the folds.

It has been the practice to interleave the
5 webs with carbon-sheets, and to attach these
carbons to a carrier, for shifting them along
after the typing of a form is completed,
preparatory to typing upon the next form.
It has also been the practice to mount slit-
10 ting knives upon the carbon-carrier, so as
to slit the web automatically at the opera-
tion of stripping the carbons.

The multiple-ply web is thus caused to
15 consist of loose plies at the intake side of the
platen, whereby some of the advantage of
fan-folding the plies is lost. To overcome
this difficulty, slitting knives have been ar-
ranged between the carbon-carrier and the
20 platen, thereby substantially reducing the
length of the split-apart plies at the intake
side of the platen, and maintaining the web
in whole condition that much longer.

One of the main features of the present in-
vention relates to simple, practical and in-
25 expensive means, readily adapted to exist-
ing machine, for slitting the web into sepa-
rate plies at the delivery side of the platen.

The invention is shown applied to a ma-
chine of the type disclosed in the Wernery
30 & Smith Patent, No. 1,132,055, dated March
16, 1915, in which the typewriter platen is
elevated to permit the webs to be straight-
ened out, for making it practicable to strip
the carbons along the web.

35 The practice is taken into account of sever-
ing the multiple-ply web transversely at the
completion of the typing of each form. This
severing is usually attended to after the car-
bons have been shifted to position for typing
40 the next form; and at such a time the lead-
ing edge of the web usually stands at a
height about level with the top of the platen.
This condition presents the problem of pre-
senting the fold-slitting knives within the
45 plies of the web, without interference of the
slitting knives with the transverse web-
severing knife, and without encountering
still other difficulties. It is an object of the
invention to overcome all these difficulties
50 and to avoid the necessity of rethreading the
fan-fold web upon the slitting knives
preparatory to performing each slitting op-
eration.

According to the present invention, the

points of the slitting knives always remain 55
between the web-plies. At the conclusion of
the operation of slitting any form, said
points are caused to project or advance a
certain distance between the plies in the
succeeding untyped form of the web. This 60
avoids the necessity of rethreading them at
every operation; and interference between
the slitting knives and the web-severing
knife is also avoided; while the folded web
remains integral up to about the printing 65
point, and preferably until after the web has
passed the printing point, so that the ad-
vantages of fan-folded webs are all preserved.

To achieve these results, the slitting
knives are mounted at the delivery side of 70
the platen. In inserting the web into the
machine, the knives are inserted properly
between the plies; the latter preferably being
preliminarily slit at the leading end of the
web, so that they may be spread open for 75
the insertion of the knives. The web-slitt-
ers, however, after the introduction of the
slitting knives, as already explained, stand
just below the top of the second form, as the
first form is positioned by the gage which is 80
provided for gaging the leading end of the
web. The first form on the web need not be
typed, but may be regarded as waste. The
second of the forms is typed. The knives re-
main idle in normal positions during the 85
line-by-line advance of the web which oc-
curs at the typing of said second form.

The folded side edges of this first web-
form may be slit by hand, if desired, before
inserting the same into the machine, and the 90
slitting may extend down for some distance
into the top portion of the second form to
give clearance for the slitting knives here-
in described; the knives subsequently pro-
ducing their own clearances, as will be ex- 95
plained.

When the typing of the second form is
complete, and the web is gaged to position
for severance and for beginning the typing
of the first line on the third form, the slit-
ting knives are pulled downwardly, thereby
slitting the folds of said second form. This
slitting proceeds down to an excessive extent,
bringing the knife points to positions some-
what below the top of the third form, where-
by a knife-clearance is cut in the tops of 100
the third-form plies. The use of this clear-
ance will presently appear. Still prior to
105

typing the third form, the slitting knives are returned up to normal positions and the first form on the web may now be torn off and thrown away.

- 5 The typing of said third form now proceeds, and the separated plies advance past the stationary slitting knives, which remain idle between the plies during the line-by-line typing of said third form. By the time 10 that the third form is completed, or nearly so, the knife points will have positions between the plies of the third form, at its upper portion. That is, the points will be below the second form and within the clearances already mentioned in the top of the third form. The web-severing knife is above the fold-slitting knives, so that when the web is positioned for severance, the slitting knives will be entirely within the third form. 15
- 20 At the completion of the typing of said third form, therefore, the leading edge of the second form is brought up against the top gage, and the carbons are stripped back to the fourth form. Then the slitting knives 25 are drawn down thus slitting the folds of the third form and forming clearances in the top of the fourth form. The knives then return up to normal positions, and the second form is torn off, and the typing of the fourth form proceeds, the slit third form remaining 30 in the machine.

The slitting knives may be mounted upon a truck or carrier which is mounted to extend across a slitting and web-severing table 35 at the delivery side of the platen, the table preferably extending upwardly and rearwardly from the platen. This table is swung forwardly and downwardly, together with the platen, preparatory to the carbon-stripping operation. Said stripping blade carrier is mounted for easy movement up and down said table, and is normally supported in its upper position, in which it stands just below or clear of the transverse web-severing 40 knife.

To accommodate forms of varying lengths, the position of the slitter truck and of the transverse web-severing knife may be adjusted up and down said table.

50 Other features and advantages will hereinafter appear.

In the accompanying drawings,

Figure 1 is a perspective detail showing one end of the slitting-knife truck.

55 Figure 2 is a sectional side elevation illustrating the operation of typing the second form on the web.

Figure 3 shows the web straightened out and the carbons as having been stripped to 60 position for typing the third form.

Figure 4 shows the slitting stroke of the fold-slitter as having been completed, whereby the second form on the web has been slit, and the cuts have been extended down into 65 the top portion of the third form.

Figure 5 shows the same as Figure 4, but shows the slitting truck as having been returned to normal position, with its blades remaining within the folds of the second form at its top portion.

70 Figures 4 and 5 show the top edge of the first form as brought to a gage for severing said form, and to the proper point for beginning the typing of the third form. Figure 5 shows the operation of tearing off the first form. When the webs have advanced a form length from the Figure 5 position, the blades will occupy clearances or slotted upper portions of the folds in the third form.

75 Figure 6 is a front elevation of the machine seen in Figure 2.

Figure 7 is a sectional plan illustrating the truck which carries the slitter blades.

80 Figure 8 is a sectional plan, showing the adjustable web-severing knife and appurtenances.

The fan-fold web 10 is threaded through the usual carbon-carrier 11, the sheets of carbon 12 interleaved with the plies of work-web. From the carbon-carrier the web runs forwardly and downwardly around a platen 13, as illustrated in said patent to Wernery & Smith. The web is divided into forms, of which the second is being filled up by means of types 14 at Figure 2. The first or initial form, whose lower boundary is indicated at 15, does not need to be typed; but after serving the hereinafter described temporary purpose it may be torn off and thrown away. 100 The typing of the second form proceeds, the platen 13 feeding along with its carriage 16, as set forth in said patent.

105 Upon the completion of the typing of the second form, the platen 13 is swung upwardly, as at Figure 3, and the leading edge of the first form is brought up to a gage 17, which is adjustable along a staff 18, the latter extending up from a slitting and severing table 19, that is erected at the delivery side of the platen upon a swinging platen-frame 40 which is mounted upon the carriage 16. Having adjusted the leading edge of the web to the gage 17, the operator 110 detains the web at that point while he pushes back the handle 21 usually provided upon the carbon-carrier 11, until it is arrested by an adjustable gage 22, thus stripping the carbons 12 from the second form, whose bottom boundary is indicated at 23, to the third form, preparatory to typing the latter. Then the platen is swung down to normal position, the table 19 returning to its normal 115 upwardly and rearwardly inclined position, as at Figure 4. At this time the stripped or shifted carbons now stand just above the printing line on the platen, Figure 4. Before typing, however, opposite handles 24 are grasped and pulled downwardly along the table 19, thereby slitting apart the fan-

130

fold webs; these handles 24 being provided upon a vertically movable truck 25, Figure 7, overlying the table and extending there-across, Figure 6. Upon the opposite sides 5 of the truck are mounted fold-slitting blades 26, inserted within the folds of the web and pointing forwardly and downwardly, so as to slit the web by a downward movement of the blades toward the platen from the position 10 at Figure 6 to the position at Figure 4. The truck is guided for parallel movement by means of pinions 27 mounted upon the ends of a shaft 28 and meshing with stationary racks 29, mounted on opposite side edges 15 of the table 19; said shaft journaled in brackets 30 depending from the truck 25. The blades are clamped together by thumb-nuts 31 at opposite ends of the table, fitted upon studs 32 extending upwardly from the 20 ends of the truck 25, the blades being preferably spaced by washers 33.

The downward slitting movement of the truck is continued until the blades reach the position seen at Figure 4, showing that 25 the slitting has been prolonged past the second form, for a considerable depth, into the upper portion of the third form, but not far enough for the blades to foul the carbons in the third form. Then the handles 30 are relieved of pressure, and a spring 34 wound about the shaft 28 lifts the truck to normal position against a stop bar 35, which extends across the table and above the same and is adjustably secured thereto 35 by thumb-screws 36. Said thumb-screws and bar may work in the same grooves 37 in the opposite racks 29 that serve as tracks for the slitting-knife truck; and the thumb-screws 36 may be threaded into lugs 38 secured 40 to the ends of said stop bar and bearing upon the top edges of the racks.

The slitting operation having been completed, the typing may now proceed line by line until the second form is completely 45 typed, the web being drawn into the machine by the platen and the usual feed-rolls 39, and feeding up freely along the table 19 past the slitting knives 26, which remain idle in normal position during the typing of 50 each form. At the conclusion of the typing of the second form, the knives stand entirely below said form, and between the plies of the third form at the upper portion thereof, being located in the clearances that were produced 55 as described at the conclusion of the slitting operation seen at Figure 4. At this point the platen is again raised, the parts brought to the position at Figure 3, the top of the second form being brought to the 60 gage 17, and the carbons are shifted back to the fourth form. The platen and its swing frame 40 are returned to normal positions together with the table; the second form is torn off by knife 41, and the typing 65 of the fourth form begins.

The web-severing knife-blade 41 moves up and down the table to accommodate forms of different lengths, and the gage 17 may be adjusted accordingly. The knife-blade 41 may be secured upon the above-described lugs 38, so that both the stop bar 35 and the knife-blade may be adjusted together up and down the table, thus providing for a regulation of the length of the stroke of the fold-slitter, as well as of the length of 70 the form. The racks 29 extend alongside the table 19 to form a framework for the table. At the upper ends the racks are joined by a rigid cross-bar 42, conducing to the stiffness of the entire table structure; the 80 bar being secured at its ends by screws 43 to the ends of the racks. At its lower end the table may be supported by a bracket 44, which may include a cross-bar 45 and pairs of arms 46 and 47 extending up from 85 the ends thereof and fixed to the table; the arms 47 being secured by screws 48 to the side members of the swinging platen-frame 40.

The slitting strokes of the slitting truck 90 may be limited by stops 49, secured upon the lower ends of the racks 29.

Variations may be resorted to within the scope of the invention, and portions of the improvements may be used without others. 95

Having thus described my invention, I claim:

1. A fan-fold typewriting machine including a platen, means for shifting the carbons along the fan-fold web, and means at the delivery side of the platen and movable relatively thereto for slitting the folds of a stationary web form by form after the typing thereof. 100

2. A fan-fold typewriting machine including a platen, means for shifting the carbons along the fan-fold web, and manually-operable means at the delivery side of the platen and slidably mounted in position for slitting the folds of a stationary web-form which 110 has been typed previously to the last typed form.

3. A fan-fold typewriting machine including a platen, means for shifting the carbons along the fan-fold web, reciprocating means 115 at the delivery side of the platen and mounted in position for slitting the folds of a stationary web-form which has been typed previously to the last-typed form, and a device for severing said slitted form from said last-typed form; said slitting means being reciprocable between said web-severing means and said platen. 120

4. A fan-fold typewriting machine including a platen, means for shifting the carbons 125 along the fan-fold web, and means at the delivery side of the platen and movably mounted in position for slitting the folds of a stationary web-form which has been typed previously to the last-typed form and at the 130

same stroke slitting the upper part of the last-typed form.

5. A fan-fold typewriting machine including a platen, means for shifting the carbons along the fan-fold web, means reciprocable at the delivery side of the platen for slitting the folds of a stationary web form by form after typing thereof, said slitting being effected by a down stroke of said slitting 10 means, and means for detaining said slitting means in normal uppermost position.

6. A fan-fold typewriting machine including a platen, means for shifting the carbons along the fan-fold web, means at the delivery side of the platen and manually operable in one direction for slitting the folds of a stationary web-form which has been typed previously to the last typed form, and a spring operable in a reverse direction for returning said slitting means to normal position.

7. A fan-fold typewriting machine including a platen, means for shifting the carbons along the fan-fold web, a table or work-rest at the delivery side of the platen, a truck mounted to move up and down along said table, and a set of fold-slitting knives on said truck.

8. A fan-fold typewriting machine including a platen, means for shifting the carbons along the fan-fold web, a table or work-rest at the delivery side of the platen, a truck mounted to move up and down along said table, a set of fold-slitting knives on said truck, a spring for returning said truck to normal uppermost position, and a stop to limit the return stroke of the truck.

9. A fan-fold typewriting machine including a platen, means for shifting the carbons along the fan-fold web, a table or work-rest at the delivery side of the platen, a truck mounted to move up and down along said table, a set of fold-slitting knives on said truck, and a stop for limiting the slitting stroke of said truck.

10. A fan-fold typewriting machine including a platen, means for shifting the carbons along the fan-fold web, means at the delivery side of the platen for slitting the folds of the web form by form after typing thereof, said slitting means including a slitting-knife truck movable towards the platen to effect the slitting, and a stop for said truck effective at a point where the slitting knives have penetrated into the folds of the upper portion of the succeeding web-form.

11. A fan-fold typewriting machine including a platen, means for shifting the carbons along the fanfold web, a table or work-rest at the delivery side of the platen, a truck mounted to move up and down along said table, a set of fold-slitting knives on said truck, and a web-severing knife above said slitting truck.

12. A fan-fold typewriting machine in-

cluding a platen, means for shifting the carbons along the fan-fold web, means at the delivery side of the platen and mounted in position for slitting the folds of a web-form which has been typed previously to the last-typed form, a device for severing said slitted form from said last-typed form; said slitting means being mounted between said web-severing means and said platen, and a leading-edge gage for locating the web in severing position.

13. A fan-fold typewriting machine including a platen, means for shifting the carbons along the fan-fold web, a table or work-rest at the delivery side of the platen, a truck mounted to move up and down along said table, a set of fold-slitting knives on said truck, a web-severing knife above said slitting truck, and a stop which limits the return stroke of the slitting truck, and the knife and stop being connected and being adjustable to vary the length of said stroke and accommodate forms of different lengths.

14. A fan-fold typewriting machine including a platen, means for shifting the carbons along the fan-fold web, a table or work-rest at the delivery side of the platen, a truck mounted to move up and down along said table, a set of fold-slitting knives on said truck, a web-severing knife above said slitting truck, a stop which limits the return stroke of the slitting truck, and the knife and stop being connected and being adjustable to vary the length of said stroke and accommodate forms of different lengths, and an adjustable leading-edge gage for the web.

15. A fan-fold typewriting machine including a platen, means for shifting the carbons along the fan-fold web, means at the delivery side of the platen and mounted in position for slitting the folds of a web-form which has been typed previously to the last-typed form, a device for severing said slitted form from said last-typed form; said slitting means being mounted between said web-severing means and said platen, said severing device being adjustable towards and away from the platen, and an adjustable stop for limiting the movement of said slitting means away from the platen.

16. A fan-fold typewriting machine including a platen and a work-rest or table at the delivery side of the platen, a web-severing knife upon said table in position for severing the next to the last typed form, a set of fold-slitting knives below said knife and constantly occupying positions between the web-plies, means for operating said knives, and means for limiting the slitting stroke of said knives after slitting into the upper portions of the folds of the succeeding form.

17. A fan-fold typewriting machine including a platen and a work-rest or table at the delivery side of the platen, a web-severing

- knife upon said table in position for severing the next to the last typed form, a set of fold-slitting knives below said knife and constantly occupying positions between the 5 web-plies, means for operating said knives, and means for limiting the slitting stroke of said knives after slitting into the upper portions of the folds of the succeeding form, the knives normally occupying positions adjacent 10 said severing knife, and extending within the slits in the last-typed form at the operation of tearing off the previously-typed web-form.
18. A fan-fold web typewriting machine 15 including a platen, a work-table or rest at the delivery side of the platen, racks at the opposite sides of the work-table, a truck mounted for movement up and down said work-table, a transverse shaft on said truck, 20 pinions on said shaft meshing with said racks, and a set of fold-slitting knives on said truck.
19. A fan-fold web typewriting machine 25 including a platen, a work-table or rest at the delivery side of the platen, racks at the opposite sides of the work-table, a truck mounted for movement up and down said work-table, a transverse shaft on said truck, 30 pinions on said shaft meshing with said racks, a set of fold-slitting knives on said truck, and means for operating said truck.
20. A fan-fold typewriting machine including a platen, means for shifting the carbons along the fan-fold web, a table or work- 35 rest at the delivery side of the platen, a truck mounted to move up and down along said table, a set of fold-slitting knives on said truck, and a swinging frame upon which said platen is mounted for straightening out 40 the web preparatory to shifting the carbons therealong; said table and said slitting means being mounted upon said swinging frame.
21. In a typewriting machine, the combination of a rotatable platen operable to feed an unsevered fan-folded web line by line, and means slidable relatively to the platen for slitting a fold in the typed web at the delivery side of the platen. 45
22. In a typewriting machine, the combination of a rotatable platen operable to feed an unsevered fan-folded web line by line, and a slitter disposed above the platen and operable relatively to the platen for slitting the folds of a stationary typed web at the 50 delivery side of the platen. 55
23. In a typewriting machine, the combination of a rotatable platen operable to feed an unsevered fan-folded web to a printing position for typing, independently-movable 55 slitting devices disposed at opposite edges of the web for slitting a fold therein after typing, and means for operatively connecting the slitting devices for a unitary slitting movement. 60
24. In a typewriting machine, as a means for producing manifold copies from a fan-folded web, the combination with a platen operable to line-feed the fan-folded web, of a fold-slitting device supported over the delivery side of the platen and operable towards the platen to slit the folds of the stationary typed web, and a cross-knife having a fixed position relatively to the platen and operative to sever the slitted and typed 70 forms from the body of the fan-folded web, said slitter being between the cross-knife and the platen. 75

BURNHAM C. STICKNEY.
